(57) **CLAIM**

The ornamental design for a light directing device, as shown.

DESCRIPTION

FIG. 1 is a perspective view of a light directing device.

FIG. 2 is a front view of the light directing device FIG. 1.

FIG. 3 is a back view of the light directing device FIG. 1.

FIG. 4 is a right side view of the light directing device FIG. 1.

FIG. 5 is a left side view of the light directing device FIG. 1.

FIG. 6 is a top view of the light directing device of FIG. 1; and,

FIG. 7 is a bottom view of the light directing device of FIG. 1.

The dashed lines depict portions of the light directing device or environment that form no part of the claimed design.
